UNITED STATES PATENT OFFICE.

THOMAS VERDUGO, OF MONTEREY, CALIFORNIA, ASSIGNOR OF ONE-FOURTH TO
WILLIAM H. ESTABROOK, OF MONTEREY, CALIFORNIA.

UMBRELLA.

1,299,877.

Specification of Letters Patent.

Patented Apr. 8, 1919.

Application filed July 31, 1918. Serial No. 247,622.

To all whom it may concern:

Be it known that I, THOMAS VERDUGO, a citizen of the United States, residing at Monterey, in the county of Monterey and 5 State of California, have invented certain new and useful Improvements in Umbrellas, of which the following is a specification.

This invention is an umbrella and has for its principal object the production of a 10 collapsible structure of this nature which may be folded to occupy only a minimum amount of space when not in use.

Another object of this invention is the production of an umbrella wherein the frame 15 work is so constructed as to hold the covering in an extended position when the same is dry, although after the cover is dried, the ribs of the umbrella may be collapsed or folded to occupy only a minimum amount of 20 space.

Another object of this invention is the production of an umbrella wherein the supporting ribs are each composed of a primary and auxiliary section, the auxiliary section 25 being slidable upon the primary section for supporting the cover when the umbrella is in use, although the auxiliary section may slide upon the primary section to occupy only a minimum amount of space when the 30 umbrella is not in use.

Another object of this invention is the production of an umbrella wherein the supporting ribs are reinforced by braces when the device is in an open condition, and these 35 braces will also assist in properly holding the umbrella in a collapsed condition when the same is not in use.

A still further object of this invention is the production of an umbrella wherein the 40 tip of the staff is slidably mounted and is provided with a latch, whereby the latch may grip an auxiliary runner for holding the umbrella collapsed when the same is not in use, although when so desired, the tip may be 45 shifted to release the runner and thus allow the device to be shifted to an extended position for use.

One practical form of construction and assembly of the present invention will be hereinafter described and is illustrated in the accompanying drawings, in which—

Figure 1 is a side elevation of a portion of the staff and of a supporting rib and braces.

Fig. 2 is a central longitudinal section

through the umbrella illustrating in elevation one supporting rib and the braces associated therewith.

Fig. 3 is a fragmentary detail perspective view of a portion of one of the supporting 60 ribs, illustrating the construction of the primary and auxiliary section, and

Fig. 4 is a fragmentary detail perspective view of the outer ends of the primary and auxiliary sections, of one of the supporting 65 ribs, showing the ribs in a collapsed condition.

In the preferred embodiment of the present invention, about to be described, it will be seen that the staff is indicated in general 70 at 5 and comprises a main section 6 and a number of secondary sections 7 to allow the staff to be the usual length of umbrellas now in use. It will be noted that the main section 6 is provided with a solid end 8, having 75 a pocket 9 therein, whereby the threaded stem 10 projecting from the secondary section 7 may be screwed thereinto for holding the sections together, as illustrated in Fig. 2. The connection between the other sections is 80 of the same nature and for this reason it is thought that the description of the connection of a pair of sections will be sufficient to illustrate the connection of the several sections which constitute the staff. 85

The usual metallic head 11 is fixed upon the main section 6 adjacent the outer end thereof, as illustrated in Figs. 1 and 2 and is provided with extensions 12 thereon provided with notches 13 in which the retaining 90 wire 14 is carried for holding the supporting ribs in engagement with the head 11 in the usual manner. It will be noted that each supporting rib comprises a primary section 15 and an auxiliary section 16. The primary section 15 is circular in cross section, as shown clearly in Fig. 3 and is provided with a longitudinally extending slot 17. The primary section 15 is pivotally mounted upon the wire 14 which is held upon extensions 12 and in this way pivotally supporting the ribs upon the head 11, as shown in Fig. 2. This primary section 15 is also provided with a sleeve 18 at its outer end, illustrated in Figs. 1, 2 and 4. 95 100 105

The auxiliary section 16 of the supporting rib has a lug 19 upon its inner end, a ball 20 being carried by the lug 19. This lug 19 extends through the slot 17 of the primary section 15, while the ball 20 is movably 110

mounted in the interior of this primary section. It will further be noted that the auxiliary section 16 is slidably mounted through the sleeve 18 formed on the primary section 15, whereby the section is slidably mounted upon the primary section. It is obvious the positioning of the ball within the primary section 15 will protect the covering material from wear by the movement of the ball, although it is obvious the auxiliary section may be moved to an extended position or to a collapsed position, being guided in its movement by the ball 20 and the sleeve 18. The primary runner 21 is slidably mounted upon the staff 5 and is provided with retaining elements 22 thereon, whereby the lower end of a retaining rib 23 may be connected thereto. The outer end of this brace 23 fits between the parallel ears 24 carried by the auxiliary section 16 at its inner end and a pin or other element 25 may be passed through the ears and also the outer end of this brace 23, for connecting these elements together. By referring to Fig. 1, it will be noted that when the supporting rib is in extended position for use, the brace 23 will engage the same at a point approximately intermediate the ends thereof, thus reinforcing the same. An auxiliary runner 26 is also slidably mounted upon the staff 5 and has retaining elements 27 thereon, whereby the inner end of an auxiliary brace 28 may be connected thereto, as indicated at 29. The outer end of this brace rib 28 is connected to the brace 23 intermediate its ends by the ear and pin connection as indicated in general at 30. While only one supporting rib, together with its associated braces has been described and shown, it is obvious that any desired number of these assemblies may be employed in order to form a complete and operative construction, although the description of one assembly is sufficient to disclose the construction of all.

The tip 31 extends from the outer end of the main section 6 of the staff, as illustrated in Fig. 2. The main section 6 is provided with a pair of apertured septa 32 adjacent its outer end, and a coiled spring 33 is interposed between these septa. One end of the coiled spring bears upon the inner septum, while the opposite end is connected to the tip 31, whereby the resiliency of this coiled spring will normally urge the tip 31 outwardly. A finger 34 extends from the inner end of the tip and is provided with a head 35. This head 35 is provided with a beveled surface 36 which bears upon the block 37 carried by the main section 6. It will also be noted that the main section 6 is provided with an opening 38 through which the head 35 normally extends. It is obvious that when the tip 31 is urged inwardly, against the tension of the coiled spring 33,

it will cause the resilient finger 34 to yield by the riding of the head 35 upon the surface of the block 37, thus causing the head to be retracted into the interior of the main section 6.

When the device is not in use, the ribs may be collapsed and the braces folded as indicated in Fig. 2, while the secondary sections of the staff may be disjointed whereby the umbrella may be carried in a minimum amount of space, as for instance, in a suitcase, since the braces are so formed as to cause the ribs and the covering thereof to occupy only a minimum amount of space. At this time, the runner 26 will be engaged by the head 35 and thus it will be seen that the device will be positively held in a closed condition.

When however, it is desired to use the umbrella, the tip 31 may be forced into the main section 6 of the staff, thus causing the head 35 to ride upon the surface of the block 37, whereby the head 35 will disengage the runner 26. Therefore, the runners 26 and 21 may move toward the opposite end of the staff which at this time should be assembled, by the connection of the several sections together. The movement of the runners toward the opposite end of the staff causes the auxiliary section 16 of each supporting rib to slide upon the primary section thereof to an extended position, as indicated in dotted lines in Fig. 1. Any form of covering desired may be carried upon the supporting ribs, being secured to the outer ends of the auxiliary section and also adjacent the outer end of the main section 6 of the staff. The runners may then be returned toward the outer end of the main section 6 and for this reason the supporting ribs will be swung outwardly to an extended position, as indicated in full lines in Fig. 1. At this time, the braces 23 will be holding the supporting ribs intermediate their ends, while the brace ribs 28 will also be holding the braces 23 and also will prevent the auxiliary section from slipping or sliding inwardly toward a collapsed condition when the umbrella is in use.

In order to retain the braces 23 in a set up condition, a runner catch 39 is fixed within the main section 6 of the staff and is provided with a head 40 extending outwardly therefrom. When the umbrella is in use, the runner 21 will rest upon the head 40 and in this way the several ribs will be held against accidentally collapsing.

When it is desired to collapse the umbrella, after it has been used and while it is still wet, the head 40 is pressed inwardly to release the runner 21. The runners 21 and 26 will then move toward the position shown in dotted lines in Fig. 1 and the collar 21 may be moved into engagement with the head 41 of a runner similar in construction

to the catch 39. At this time, the supporting rib will still be in an extended condition to hold the covering thereon in an extended condition to allow the same to 5 quickly dry.

After the cover has dried, the auxiliary sections 16 may be slid toward the inner ends of the primary sections 15, thus causing the supporting ribs to be collapsed. The 10 runner 26 to which the braces 28 are connected will then engage the head 35 of the finger connected to the tip 31, whereby the runner 26 will be held against accidental shifting and the ribs will be held in a collapsed condition.

From the foregoing description, it will be seen that a very simple and efficient umbrella has been provided wherein the ribs are constructed so as to be movable to extended positions to hold the cover in an extended condition when in use, although when desired, the several ribs may be collapsed and returned to a folded condition and will be positively retained in this condition by 25 the means connected to the spring pressed tip.

The foregoing description and the drawings have reference to what may be considered the preferred, or approved, form of 30 my invention. It is to be understood that I may make such changes in construction and arrangement and combination of parts, materials, dimensions, et cetera, as may prove expedient and fall within the scope of the 35 appended claims.

Having thus fully described my invention, what I claim as new and desire to secure by Letters Patent, is:—

1. In an umbrella, the combination of a 40 staff, a runner slideable on said staff, supporting ribs foldably mounted upon said staff, braces connected to said supporting ribs and to said runner, whereby as the runner is shifted the supporting ribs may be 45 moved to an extended or closed position, a movable tip carried by said staff, and latching means associated with said tip for engaging said runner and holding the same in a set position when the supporting ribs are 50 folded to a collapsed position, thus holding the device inoperative.

2. In an umbrella, the combination of a 55 staff, a runner movable upon said staff, supporting ribs foldably mounted upon said staff, braces connected to the supporting ribs and to said runner, a spring pressed tip carried by said staff, an engaging means

carried by said tip for releasably engaging said runner for holding the same in a set position, thus retaining the supporting ribs 60 in a collapsed inoperative position, and said tip being capable of being shifted to cause said means to disengage the runner and allow the same to be moved when the ribs are to be moved to an operative position. 65

3. In an umbrella, the combination of a staff, a runner mounted upon said staff, supporting ribs foldably mounted upon said staff, braces connected to said supporting ribs and said runner, a tip carried by said 70 staff, a finger extending from the inner end of said tip and having a head thereon, said head extending from the staff to releasably engage the runner and hold the same in a set position, whereby the ribs will be held 75 in an inoperative folded position, a block carried within the staff and engaging said head, whereby as said tip moves the head upon the block, the head will be shifted to release the runner, thus allowing said rib 80 to be moved to an extended operative position.

4. In an umbrella, the combination of a staff, a runner movable upon said staff, supporting ribs foldably mounted upon said staff, braces connected to said ribs and said runner, said staff having a pair of spaced apertured septa carried therein, a tip carried by the end of the staff and projecting through said septa, a spring positioned between the septa and bearing upon one septum and connected to said tip for normally urging the same in one direction, a finger extending from the inner end of said tip and having a head thereon, said head having 95 a beveled surface, a block carried within the staff and having a beveled surface engaging the beveled surface of said head, said head extending from said staff to releasably engage said runner to hold the ribs in a folded inoperative position, although said tip may be forced inwardly against the tension of said spring, thus causing the head to ride upon the block and be retracted from engagement with the runner, thus allowing the 100 runner to move and consequently allow the 105 ribs to move to an operative position.

In testimony whereof I affix my signature in presence of two witnesses.

THOMAS VERDUGO.
